(57) **CLAIM**

The ornamental design for a headlamp cover lens, as shown and described.

DESCRIPTION

FIG. 1 is a perspective view of a headlamp cover lens suitable for use on a left side of a motor vehicle according to a first embodiment of our new design;

FIG. 2 is a front elevational view of the headlamp cover lens of FIG. 1;

FIG. 3 is a left side elevational view of the headlamp cover lens of FIG. 1;

FIG. 4 is a top plan view of the headlamp cover lens of FIG. 1;

FIG. 5 is a perspective view of a second embodiment a headlamp cover lens our new design, with the headlamp cover lens for the opposite side being depicted in the first embodiment;

FIG. 6 is a front elevational view of the headlamp cover lens of FIG. 5;

FIG. 7 is a right side elevational view of the headlamp cover lens of FIG. 5; and,

FIG. 8 is a top plan view of the headlamp cover lens of FIG. 5.

The subject matter shown in phantom lines is hereby disclaimed and forms no part of the claimed invention.

1 Claim, 8 Drawing Sheets
